[57] **CLAIM**

The ornamental design for the aerial toy goal, as shown and described.

DESCRIPTION

FIG. 1 is a perspective view of an aerial toy goal showing my new design;

FIG. 2 is a top view thereof;

FIG. 3 is a front view thereof;

FIG. 4 is a right side elevational view thereof, the undisclosed opposite side being a mirror image;

FIG. 5 is a rear view thereof;

FIG. 6 is a bottom view thereof;

FIG. 7 is a perspective view of a second embodiment of the aerial toy goal as in FIG. 1;

FIG. 8 is a top view of FIG. 7;

FIG. 9 is a front view of back view of FIG. 7;

FIG. 10 is a side elevational view of FIG. 7, the undisclosed opposite side being identical;

FIG. 11 is a bottom view of FIG. 7;

FIG. 12 is a perspective view of a third embodiment of the aerial toy goal as in FIG. 1;

FIG. 13 is a top view of FIG. 12;

FIG. 14 is a front elevational view of FIG. 12, the undisclosed opposite side being identical;

FIG. 15 is a side elevational view of FIG. 12, the undisclosed opposite side being identical; and,

FIG. 16 is a bottom view of FIG. 12.
